KERF-CUTTING MACHINE

Thomas E. Pray, Chicago, Ill., assignor to Goodman Manufacturing Company, Chicago, Ill., a corporation of Illinois

Application September 13, 1937, Serial No. 163,565

14 Claims. (Cl. 262—28)

This invention relates to improvements in kerf-cutting machines and more particularly relates to a kerf-cutting machine which is so arranged as to eliminate the shooting operation by cutting 5 the coal seam in such a manner that it will fall of its own accord.

Among the objects of my invention are to provide a new and improved kerf cutting machine of the class described, so arranged that the machine may cut out the entire coal seam in a simplified manner and permit the coal in the seam to fall to the ground without blasting or shooting.

Another object of my invention is to provide 15 a simplified, inexpensive, and efficient construction of mining machine so arranged that the cutter bars may be positioned to cut a pair of parallel spaced kerfs one of which is adjacent the mine roof, and by a simple adjustment may cut another pair of kerfs on each side of the lowermost of said first-mentioned kerfs, one of which last-mentioned kerfs is adjacent the mine bottom.

Still another object of my invention is to provide a novel means for supporting the machine to 25 permit it to slide and cut while sliding along the mine bottom, which supporting means is adjustable to position one of the bars adjacent the roof and position the same bar adjacent the ground when it has been rotated through 30 180° about an axis extending longitudinally of the machine and which is also so arranged as to permit the height of the machine to be reduced to a minimum for transportation about the mine.

35 Other objects of my invention will appear from time to time as the accompanying specification proceeds.

My invention may be more clearly understood with reference to the accompanying drawings 40 wherein:

Figure 1 is a diagrammatic plan view of a machine constructed in accordance with my invention, in position in a working place of a mine during the cutting operation;

45 Figure 2 is a side elevation of the machine shown in Figure 1 with one of the cutter bars positioned to cut along the roof;

Figure 3 is a side elevation of the machine shown in Figure 1 showing one of the cutter bars 50 positioned to cut along the mine bottom;

Figure 4 is an enlarged side elevation of the machine shown in Figure 1;

Figure 5 is a rear end view of the machine shown in Figure 1 drawn to an enlarged scale;

55 Figure 6 is a fragmentary side elevation of the

rearward portion of the machine shown in Figure 1 and drawn to the same scale as Figure 5, with certain parts broken away and shown in section;

Figure 7 is an enlarged fragmentary plan view 5 of the forward portion of the machine with certain parts broken away and shown in section;

Figure 8 is an enlarged fragmentary longitudinal sectional view of the forward portion of 10 the machine shown in Figure 1;

Figure 9 is a sectional view taken substantially along lines 9—9 of Figure 7; and

Figure 10 is an enlarged transverse sectional 15 view of the cutter head taken substantially along lines 10—10 of Figure 4.

With reference now in particular to the drawings, the mining machine, as herein shown, operates on principles somewhat similar to the ordinary kerf-cutting machine of the room and pillar type, that is; it is provided with a pair of winding 20 drums 10, 10 on opposite sides of the rearward end thereof, each of which has a flexible cable 11 wound thereon, the flexible cable on the advance side of the machine acting as a feeding means for moving the machine across the working face during cutting, and the cable on the retreating side of the machine acting as a retarding means to hold the machine up to the face and the cutter bar in the desired relationship 25 with respect to the coal face.

The machine, as herein shown, is provided with a motor 12 and a feeding section 13 disposed rearwardly of said motor, which includes the winding drums 10, 10 driven from said motor in a manner well known to those skilled in the 30 art, and not shown or described herein since it is no portion of my present invention.

A cutting section 14 is disposed forwardly of said motor and includes a frame 15 secured to said motor and projecting forwardly therefrom.

A cutter head 16 is mounted on said frame for pivotal movement with respect thereto about an axis extending longitudinally of the machine, and has a pair of spaced cutter bars 17 and 18 projecting 40 therefrom in parallel spaced relationship with respect to each other, which have cutter chains 19 and 20, respectively, movable thereabout in closed orbital paths.

Said cutter chains are meshed with sprockets 21 and 22 respectively which are mounted on opposite ends of a shaft 45 23 which is journaled in said cutter head and driven from the motor 12 in a manner which will more clearly appear as this specification 50 proceeds.

Referring now in particular to the cutting sec- 55

tion 14 and several of the novel features of my invention, a rearwardly projecting annular portion of the cutter head 16 is mounted in an annular recess 24 for pivotal movement with respect thereto about a longitudinal axis. Said recess is formed in the forward end of the frame 15 and the projecting portion of said cutter head is retained therein by an annular ring 25 secured to the forward end of the frame 15 in a suitable manner. Said ring abuts a shouldered forward face of said rearwardly projecting annular portion of said cutter head and retains said annular portion on said frame so the entire cutter head may be rotatably moved with respect to said frame.

The cutter head 16 is turned about its axis of pivotal connection to the machine by means of pinions 26, 26 on shafts 27, 27 which are mounted in and project rearwardly from said cutter head. Said pinions mesh with an internal gear 28 keyed to the forward portion of the frame 15 adjacent the annular recess 24. Said pinions are also adapted to be selectively meshed with a spur gear 29, herein shown as being formed integral with a sleeve 30 which is feathered on a sleeve 31. Said last-mentioned sleeve is journaled in the frame 15 coaxial with the turning axis of the cutter head. Thus when said pinions are driven by power, they will walk around said internal gear and cause pivotal movement of said cutter head about an axis extending longitudinally of the machine.

The drive from the motor 12 to the sleeve 31 and spur gear 29 includes a motor shaft 32 which, as herein shown, is coaxial with the sleeve 31. A bevel gear 33 is journaled in the frame 15 for rotation about an axis parallel to the shaft 32. Said bevel gear is driven from said shaft by means of a suitable chain and sprocket drive generally indicated by reference character 34. A pair of oppositely disposed bevel gears 36, 36 are meshed with and driven from said bevel gear, and said bevel gears form a selective reversible drive for a transversely extending shaft 37 which is journaled in the frame 15 and on which said bevel gears are freely mounted. Suitable clutch means including a clutch collar 38 are provided to drive said transverse shaft from either of said bevel gears in an ordinary manner and thus reverse the direction of rotation of said shaft without reversing the direction of rotation of said motor. A worm 39 is keyed on said last-mentioned shaft which meshes with and drives a worm gear 40 keyed on the sleeve 31.

The sleeve 30 is provided with a peripheral groove 43 adapted to be engaged by a shipper yoke 44 for shifting said sleeve along the sleeve 31 and engaging the spur gear 29 with the pinions 26, 26 to turn the cutter head 16 by power.

Suitable means are provided to lock the cutter head 16 from pivotal movement and hold the cutter bars in various desired fixed cutting positions, which, as herein shown, include a pin 45 mounted in a lateral extension 46 from the cutter head 16. Said pin has teeth formed on its end which are adapted to engage suitable teeth 47, 47 formed in the forward face of the annular ring 25 and projecting forwardly therefrom. Said pin is operated by means of a suitable hand lever 48 and link 49 by means of an eccentric 50 on said lever which engages said link.

The shaft 23 and cutter chain drive sprockets 21 and 22 are selectively driven from the motor by means of a shaft 51 extending through the sleeve 31 and journaled for rotation about an

axis coaxial with the axis of rotation of said sleeve. Said shaft is driven from the forward end of the motor shaft 32 by means of a flexible coupling generally indicated by reference character 53. A bevel pinion 54 is mounted on the forward end of the shaft 51 and meshes with a bevel gear 55 freely mounted on the shaft 23. Said bevel gear is selectively connected with said shaft, for driving said shaft, by means of a jaw clutch generally indicated by reference character 56 (see Figure 8).

The cutter bars 17 and 18 are slidably mounted in grooves 57, 57 formed in cutter bar support members 58, 58 projecting from opposite sides of the forward end of the cutter head 16. Tension of the respective cutter chains 19 and 20 is adjusted by means of suitable adjusting mechanisms engaging each of said cutter bars, the construction of each of which is substantially the same so one only need herein be described. Said adjusting mechanism includes a lever arm 59 pivoted to the cutter bar support member 58 intermediate its ends. One end of said lever arm engages the rear end of the cutter bar in a slot 60 formed in the central portion thereof. The other end of said lever arm is pivoted between the furcations 61 of a bifurcated end of a threaded member 62. Said threaded member extends through a suitable opening in a forward spacing wall 63 extending between the support members 58, 58. A nut 64 is threaded on said threaded member and has a portion which extends through the wall 63. A collar 65 abuts the opposite side of said wall from the lever arm 59 and prevents translational movement of said nut with respect to said wall so that turning of said nut in one direction will slide the cutter bar in a forward direction to tighten the chain, and turning of said nut in an opposite direction will permit loosening of the chain in an obvious manner.

It may be seen from the foregoing that the cutter bars 17 and 18 are mounted on the frame 15 for pivotal movement with respect thereto about a longitudinal axis and that said cutter bars are off center from said axis so that the cutter bar 17 may be an upper cutter bar when said cutter head is in one position, and may be a lower cutter bar when said cutter head is rotated 180° to an opposite position, and so that the cutter bar 18 may cut between the kerfs cut by the cutter bar 17 and on opposite sides of the turning axis of said cutter head.

Referring now in particular to the novel arrangement for supporting the machine for slideable movement along the mine bottom so that the cutter bar 17 may be positioned to cut along the roof or floor of the mine, which is also so arranged that the height of the machine may be reduced for transportation from working place to working place, the rear end of the machine is supported on a shoe 67. Said shoe projects downwardly from the feeding section 13 and extends transversely across the rear under side thereof. The under side of said shoe is of an arcuate formation and forms an arcuate ground engaging face formed about an axis which extends transversely of the machine, which face forms a fulcrum about which the machine may pivot.

The forward end of the machine is adjustably supported on a transversely extending supporting shoe 69. Said shoe has a pair of threaded shafts 70, 70 transversely pivoted to opposite sides thereof, which shafts, as herein shown, are threaded in hubs 71, 71 of bevel gears 72, 72.

Said bevel gears are journaled on their hubs in lateral extensions 73, 73 from the forward portion of the frame 15, and are held from vertical displacement with respect to said frame 5 by means of cylindrical thrust members 74, 74, one of which engages the upper end of each of said bevel gears. Each of said thrust members depends from a cap piece 75 which encloses the top side of the respective extension 73. The 10 bevel gears 72, 72 are meshed with bevel pinions 76, 76 on opposite ends of a transversely extending shaft 77. Said shaft is suitably journaled in said frame and is selectively driven from the sleeve 31 by means of a pair of meshing helical 15 gears 78, 78 and a suitable clutch generally indicated by reference character 79. Said clutch is herein shown as being of the friction conical type and includes a conical friction engaging drum 80 feathered on the transverse shaft 77 20 and slidably moved therealong in a suitable manner for engagement with an inner frusto-conical surface 81 projecting from the helical gear coaxial with said shaft.

Thus the entire machine may be pivoted about 25 the shoe 67 by power to adjust the angle of the cutter bars 17 and 18 with respect to the ground, and position the cutter bar 17 adjacent the mine roof in seams of varying thicknesses for cutting a kerf along the roof when the cutter head 16 30 is in one position and along the ground to cut a kerf along the ground when said cutter head is rotated 180° to an opposite position.

Referring now to the use and operation of the machine described herein, when the machine is 35 positioned in the working place to feed or sump the cutter bars into the coal seam, the cutter bar 17 is first adjusted so that its outer end is adjacent the roof by rotatably adjusting the cutter head 16 to the proper position and locking 40 said cutter head in such a position and then elevating the forward end of the machine about the shoe 67 by means of the extensible supporting connection between the forward end of the machine and the shoe 69, in the hereinbefore 45 described manner. The cutter bars 17 and 18 are then sumped into the coal and fed across the coal face by means of the flexible cables 11, 11 in a manner similar to that used in sumping and feeding the common form of 50 mining machine of the room and pillar type. After said cutter bars have each simultaneously cut a kerf across the coal face, one of which kerfs is adjacent the roof and the other of which is intermediate the roof and bottom and beneath 55 the turning axis of the cutter head, the machine is withdrawn from the face and moved back to the right hand side of the working place (providing the machine is working from right to left). When the machine is so positioned the cutter 60 head 16 is rotated 180° to position the cutter bar 17 in a lowermost position with respect to the machine frame so it may be adjusted to cut along the ground and the cutter bar 18 may be positioned above the turning axis of the cutter head and above the kerf first cut by it. The 65 machine is then angularly adjusted with respect to the mine bottom by means of the adjustable shoe 69 so that the outer end of the cutter bar 17 is adjacent the mine bottom and the two cutter bars are then sumped into the coal and fed across the face in the usual manner. While 70 these second two kerfs are being cut, the cutter chains moving about their respective cutter bars will cut kerfs on each side of the lowermost kerf 75 cut in the first cutting operation which will

break down the coal intermediate the top and bottom kerfs. Thus, the entire coal seam may be mined in a simple and efficient manner eliminating the use of powder for breaking down the coal.

While I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a mining machine, a frame, a cutter head mounted thereon for rotational movement with respect thereto about an axis extending longitudinally of said frame, said cutter head having cutter bars projecting from opposite sides thereof, each of said cutter bars having a cutter chain movable thereabout, and means for adjustably supporting said frame to position said cutter bars to cut a plurality of spaced apart kerfs, one of which is along the mine roof when said cutter head is in one position and to cut a plurality of spaced apart kerfs on opposite sides of the lowermost of said first-mentioned kerfs, one of which is along the mine bottom when said cutter head is rotatably moved to an opposite position including a shoe having slidable engagement with the ground and having adjustable supporting engagement with the forward end of said frame whereby the forward end of said frame may be vertically adjusted with respect thereto.

2. In a mining machine, a frame, a cutter head mounted thereon for rotational movement with respect thereto about an axis extending longitudinally of said frame, said cutter head having cutter bars projecting from opposite sides thereof, each of said cutter bars having a cutter chain movable thereabout, and means for adjustably supporting said frame to position said cutter bars to cut a plurality of spaced apart kerfs, one of which is along the mine roof when said cutter head is in one position and to cut a plurality of spaced apart kerfs on opposite sides of the lowermost of said first-mentioned kerfs, one of which is along the mine bottom when said cutter head is rotatably moved to an opposite position including a shoe having slidable engagement with the ground and having adjustable supporting engagement with the forward end of said frame whereby the forward end of said frame may be vertically adjusted with respect thereto.

3. In a mining machine, a frame, a cutter head mounted thereon for rotational movement with respect thereto about an axis extending longitudinally of said frame, said cutter head having a cutter bar projecting from each side thereof, said cutter bars each having a cutter chain movable thereabout, and means for adjustably supporting said frame to position said cutter bars to cut a plurality of spaced apart kerfs, one of which is along the mine roof when said cutter head is in one position and to cut a plurality of spaced apart kerfs on opposite sides of the lowermost of said first-mentioned kerfs, one of which is along the mine bottom when said cutter head is rotatably moved to an opposite position including a shoe having slidable engagement with the ground and having adjustable supporting engagement with the forward end of said frame whereby the forward end of said frame may be vertically adjusted with respect thereto, and another shoe adapted to support the rearward end of said frame on the ground, said shoe having an arcuate surface engaging the ground, the axis of which extends transversely of the machine whereby said shoe may form a fulcrum about which said frame may pivot.

3. In a mining machine, a frame, a cutter head mounted thereon for rotational movement with respect thereto about an axis extending longitudinally of said frame, said cutter head having a cutter bar projecting from each side thereof, said cutter bars each having a cutter chain movable thereabout, and means for adjustably supporting said frame to position said cutter bars to cut a plurality of spaced apart kerfs, one of which is along the mine roof when said cutter head is in one position and to cut a plurality of spaced apart kerfs on opposite sides of the lowermost of said first-mentioned kerfs, one of which is along the mine bottom when said cutter head is rotatably moved to an opposite position including a shoe having slidable engagement with the ground and having adjustable supporting engagement with the forward end of said frame whereby the forward end of said frame may be vertically adjusted with respect thereto.

wardly of said motor including a cutter head mounted for rotational movement about an axis extending longitudinally of the machine, said cutter head having a pair of spaced apart cutter bars projecting from opposite sides thereof having cutter chains movable thereabout, means driven from the forward end of said motor for turning said cutter head, means driven from the forward end of said motor for driving said cutter chains about said cutter bars, and other means driven from the forward end of said motor for angularly adjusting the position of said cutter bars with respect to the ground so said cutter bars may cut a plurality of spaced apart kerfs, one of which is along the mine roof, when said cutter head is in one position, and to cut a plurality of spaced apart kerfs on opposite sides of the lowermost of said first-mentioned kerfs, one of which is adjacent the mine floor when said cutter head is in an opposite position including a shoe slideable along the ground and adapted to support the forward end of said machine for vertical adjustment with respect thereto, another shoe spaced rearwardly from said first-mentioned shoe and forming a fulcrum about which said frame may pivot, and an extensible drive connection between said motor and first-mentioned shoe.

10. In a mining machine of the class described, a motor, feeding mechanism disposed rearwardly of said motor and driven therefrom and including a winding drum having a flexible feeding member wound thereon, cutting mechanism disposed forwardly of said motor including a cutter head mounted for rotational movement about an axis extending longitudinally of the machine, said cutter head having a pair of spaced apart cutter bars projecting from opposite sides thereof having cutter chains movable thereabout, means driven from the forward end of said motor for turning said cutter head, means driven from the forward end of said motor for driving said cutter chains about said cutter bars, and other means driven from the forward end of said motor for angularly adjusting the position of said cutter bars with respect to the ground so said cutter bars may cut a plurality of spaced apart kerfs, one of which is along the mine roof, when said cutter head is in one position, and to cut a plurality of spaced apart kerfs on opposite sides of the lowermost of said first-mentioned kerfs, one of which is adjacent the mine floor when said cutter head is in an opposite position including a shoe slideable along the ground and adapted to support the forward end of said machine for vertical adjustment with respect thereto, another shoe spaced rearwardly from said first-mentioned shoe and forming a fulcrum about which said frame may pivot, and an extensible drive connection between said motor and first-mentioned shoe including a shaft disposed forwardly of said motor and extending transversely thereof, a pair of gears driven from opposite ends of said shaft, a pair of threaded shafts pivotally mounted on opposite sides of said shoe, and a threaded drive connection between said gears and shafts for causing the forward end of said mining machine to move translationally with respect to said shafts upon rotation of said gears.

11. A mining machine adapted to cut while slidably moving along a mine bottom including a motor, feeding mechanism disposed rearwardly of said motor and driven thereby and including a winding drum having a flexible feeding member wound thereon, cutting mechanism disposed forwardly of said motor including a cutter head

mounted for rotational movement about an axis extending longitudinally of the machine and having a pair of spaced apart cutter bars projecting from opposite sides thereof, said cutter bars having cutter chains movable thereabout, means driven from the forward end of said motor for turning said cutter head to position said cutter bars for cutting along the mine roof or floor, means driven from the forward end of said motor for driving said cutter chains about said cutter bars including a shaft journaled in said cutter head and having sprockets on opposite ends thereof, and other means driven from the forward end of said motor for angularly adjusting the position of said cutter bars with respect to the ground so said cutter bars may cut a plurality of spaced apart kerfs, one of which is along the mine roof, when said cutter head is in one position, and to cut a plurality of spaced apart kerfs on opposite sides of the lowermost of said first-mentioned kerfs, one of which kerfs is adjacent the mine floor when said cutter head is rotatably moved to an opposite position.

12. A mining machine adapted to cut while slidably moving along a mine bottom including a motor, feeding mechanism disposed rearwardly of and driven from said motor including a winding drum having a flexible feeding member wound thereon, cutting mechanism disposed forwardly of said motor including a cutter head mounted for rotational movement about an axis extending longitudinally of the machine and having a pair of spaced apart cutter bars projecting from opposite sides thereof, said cutter bars having cutter chains movable thereabout, means driven from the forward end of said motor for turning said cutter head to position said cutter bars for cutting along the mine roof or floor, means driven from the forward end of said motor for driving said cutter chains about said cutter bars including a shaft journaled in said cutter head and having sprockets on opposite ends thereof meshing with said chains, and other means driven from the forward end of said motor for angularly adjusting the position of said cutter bars with respect to the ground so said cutter bars may cut a plurality of spaced apart kerfs, one of which is along the mine roof, when said cutter head is in one position, and to cut a plurality of spaced apart kerfs on opposite sides of the lowermost of said first-mentioned kerfs one of which kerfs is adjacent the mine floor when said cutter head is rotatably moved to an opposite position including a shoe supporting the forward end of said mining machine for movement along the ground, and an extensible connection driven by said motor and interposed between the forward portion of said mining machine and shoe, for elevating the forward portion of said mining machine with respect to said shoe.

13. In a mining machine adapted to cut while slidably moving along a mine bottom, a motor, feeding mechanism disposed rearwardly of and driven from said motor including a winding drum having a flexible feeding member wound thereon, cutting mechanism disposed forwardly of said motor including a cutter head mounted for rotational movement about an axis extending longitudinally of the machine and having a pair of spaced apart cutter bars projecting from opposite sides thereof, said cutter bars having cutter chains movable thereabout, means driven from the forward end of said motor for rotatably adjusting said cutter head to position said cutter bars for cutting along the mine roof or floor, means driven

- from the forward end of said motor for driving said cutter chains about said cutter bars including a shaft journaled in said cutter head and having sprockets on opposite ends thereof, and 5 other means driven from the forward end of said motor for angularly adjusting the position of said cutter bars with respect to the ground so said cutter bars may cut a plurality of spaced apart kerfs, one of which is along the mine roof, when 10 said cutter head is in one position, and to cut a plurality of spaced apart kerfs on opposite sides of the lowermost of said first-mentioned kerfs, one of which kerfs is adjacent the mine floor when said cutter head is rotatably moved to an 15 opposite position including a shoe adapted to slidably engage the ground and support the forward end of said mining machine for adjustment with respect thereto, another shoe spaced rearwardly of said first-mentioned shoe and forming a fulcrum about which said frame may pivot, and an extensible supporting connection between the forward end of said mining machine and first-mentioned shoe, the extension of which is controlled by said motor. 20
- 25 14. In a mining machine adapted to cut while slidably moving along a mine bottom, a motor, feeding mechanism disposed rearwardly of and driven by said motor and including a winding drum having a flexible feeding member wound thereon, cutting mechanism disposed forwardly of said motor including a cutter head mounted for rotational movement about an axis extending longitudinally of the machine and having a pair of spaced apart cutter bars projecting from opposite sides thereof, said cutter bars having cutter chains movable thereabout, means driven from the forward end of said motor for turning said 30
- 35 cutter head to position said cutter bars for cutting along the mine roof or floor, means driven from the forward end of said motor for driving said cutter chains about said cutter bars including a shaft journaled in said cutter head and having sprockets on opposite ends thereof meshing with said cutter chains, and other means driven from the forward end of said motor for angularly adjusting the position of said cutter bars with respect to the ground so said cutter bars may cut a plurality of spaced apart kerfs, one of which is along the mine roof, when said cutter head is in one position, and to cut a plurality of spaced apart kerfs on opposite sides of the lowermost of said first-mentioned kerfs when said cutter head is in an opposite position one of which kerfs is adjacent the mine floor, including a shoe adapted to slidably engage the ground and support the forward end of said mining machine for adjustment with respect thereto, another shoe spaced rearwardly of said first-mentioned shoe and forming a fulcrum about which said frame may pivot, and an extensible supporting connection between the forward end of said mining machine and first-mentioned shoe, the extension of which is controlled by said motor, said supporting connection including a shaft disposed forwardly of and extending transversely of said motor, a pair of gears driven from opposite ends of said shaft, a pair of threaded shafts pivotally mounted on opposite sides of said shoe, and a threaded drive connection between said gears and shaft for causing the forward end of said mining machine to move translationally with respect to said shafts upon rotation of said gears. 30
